UNITED STATES PATENT OFFICE.

THOMAS MANLEY, OF PRINCE ALBERT, SASKATCHEWAN, CANADA.

SINGLE-TOOTH DOG FOR GRIPPING LOGS.

No. 877,208.

Specification of Letters Patent.

Patented Jan. 21, 1908.

Application filed April 19, 1907. Serial No. 369,122.

To all whom it may concern:

Be it known that I, THOMAS MANLEY, of the city of Prince Albert, in the Province of Saskatchewan, Canada, painter, have invented certain new and useful Improvements in Single-Tooth Dogs for Gripping Logs, of which the following is the specification.

My invention relates to single tooth dogs, carried by or within the knee of the head block of a saw mill carriage, and the objects of the invention are, firstly, to provide dogs which are easily removable from the supporting frame within the knee in event of the breakage of a dog, secondly, to provide a simple, easily constructed dog which can be made with little trouble in the ordinary blacksmiths shop, and lastly, to provide a framework and operating mechanism for two sets of dogs, whereby when operated, one set is thrown outwardly and downwardly, and the other outwardly and upwardly.

The invention consists essentially of a central plate or support adapted to slide within the hollow knee of the headlock, the said plate being formed with a facially enlarged front portion having on the one side a series of similar transverse, arcuate slots or guides, and on the other a similar set of slots with the arc reversed and further having on either side a set of horizontal slots disposed between the aforesaid guides, sets of single tooth dogs adapted to slide within the arcuate slots, removable side plates retaining the dogs within the guides, a removable vertical arm connecting the individual dogs of the respective sets, and means controlled by a lever for throwing the arms forwardly and backwardly, the parts being arranged and constructed as hereinafter more particularly described.

Figure 1 is a perspective view of a headlock carrying a hollow knee fitted with my invention, a part of the knee being broken away to show construction and the teeth being shown in the outer position. Fig. 2 is an enlarged side view of my invention applied within a hollow knee, the side face of the knee being torn away and portions of the side plate and arm being broken away to show construction. Fig. 3 is a reverse view of my invention to that shown in Fig. 2, the opposite side of the knee being torn away and the side plate completely removed. Fig. 4 is a side view of a hollow knee fitted with my dogs showing a modified form of operating links to that exposed in the preceding figures.

Fig. 5 is an end view of the knee showing the center plate, dogs, and side plates in position. Fig. 6 is an enlarged, detailed, perspective view of one of the right hand dogs. Fig. 7 is a detailed perspective view of one of the vertical arms.

In the drawings like letters of reference indicate corresponding parts in each figure.

A ⁶⁵ A¹ represents the framework of the sawmill carriage. B is a steel girder log seat passing across between the members A A¹ and strongly bolted thereto.

C is the headblock slidable on the log seat and carrying a hollow knee C¹. ⁷⁰

C² C³ are the ordinary lever and quadrant carried by the headblock for throwing the headblock forwardly and backwardly on the log seat, the parts of which form no part of this invention, and need no further description. ⁷⁵

D is a central plate adapted to slide within the hollow knee from the rear, the said plate having two facial enlargements D' D² on either side of the front edge. ⁸⁰

E are studs extending from either side of the central plate and are designed to allow the center plate to pass easily within the knee.

F F' F¹ F¹ are transverse arcuate slots formed within the facial enlargement of the center plate. One of the sets F F has all of the slots arranged with the curve turned downwardly, and the other set F¹ F¹ (on the opposite side of the center plate) has the slots reversed or turned upwardly. It is to be noted that the slots are identical, being outlined by arcs of equal radius. ⁸⁵ ⁹⁰

G G¹ are dogs, said dogs being formed to fit the slots F F¹ respectively, and have their forward end sharpened or pointed and their rear end formed with a stud as at G². In this wise the dogs are divided into two sets, there being what I term a right hand set G G, and a left hand set G¹ G¹, and it will further be noted that the studs G² extend outwardly from the face of the dog. ⁹⁵ ¹⁰⁰

H H¹ are bars having openings H² to admit of the studs G² of the dogs, there being a bar on either side of the center plate.

G³ are studs extending outwardly from the face of the bars and are sufficient in depth to just clear the side faces of the knee, in this way serving to hold the bars H H¹ securely in position once they are within the knee. ¹⁰⁵

I I¹ are side plates adapted to retain the dogs within the slots the said plates being removably secured to the facial enlargement. ¹¹⁰

by means of studs I^2 extending therefrom. When in position the side plates are prevented from loosening by the inner faces of the knee.

5. $J^1 J^1$ are bosses extending in sets on either side of the center plate, and $K K, K^1 K^1$ are sets of bell cranks pivotally supported by the respective sets of bosses. K^2 are pins passing through the boss and hold the bell crank in position.

10. $L L, L^1 L^1$, are horizontal slots cut in the facial enlargement of the center plate, and $M M, M^1 M^1$, are links connecting respectively, one arm of each of the bell cranks to the vertical bars $H H^1$. The said links are adapted to operate backwardly and forwardly within the slots and the connection between the link and the arm is simply through a stud extending from the link into an opening in the arm. $N N^1$ are vertical links connecting the remaining arms of the bell cranks in pairs.

15. O is a handle pivotally supported on the center plate having its lower end bent inwardly and bifurcated and straddling the center plate.

20. $P P^1$ are links pivotally connecting the vertical links $N N^1$ respectively, with the bifurcated ends $O^1 O^2$ of the handle O .

25. 30. Q are set screws extending through the knee on its upper and side faces, such screws being adapted to retain the center plate in working position. It will be noticed that one set of the side screws abut the bosses E when screwed in.

35. 40. In Fig. 4 I have shown a second form of link mechanism but the operation of the dogs and the dogs themselves are of the form as hereinbefore described. Instead of a bell crank I have pivoted two sets of straight arms $R R^1$, one on either side, and to these are connected links $S S^1$, the links S^1 being pivoted to the links S , and the link S in turn pivoted to the handle T fulcrumed at T^1 to the headblock C . The change from the bell cranks to the straight link simply requires a horizontal pull instead of a vertical lift to throw out the dogs, as will readily be seen in the drawings.

45. 50. In some cases the operator prefers the lever controlling the dogs to be somewhat back from the knee. In Fig. 1 this would simply be a matter of adding an extra link between the lower portion of the handle O and a controlling handle operating further back on the headblock, such as at T .

55. 60. It will be noted that in case of a dog breaking it is a very simple matter to insert a new one as neither the side plates nor the vertical arms are riveted in position. To take out a dog all that it is necessary to do is to undo the screws, and press or pull backwardly the central plate which carries the dogs. The bars $H H^1$ and the plates $I I^1$ can be pulled or lifted off freely and then the

broken dog can be removed. If a supply of dogs is kept on hand the time lost in replacing a broken dog is very small, and this is an important item.

What I claim as my invention is:

1. In a device of the class described the combination with the knee of a headblock, of a center plate adapted to slide within the knee, slidable dogs carried within guides in the center plate, removable side plates retaining the dogs in the guides, means for holding the center plate within the knee and means for operating the dogs forwardly and backwardly, as and for the purpose specified. 70

15. 2. In a device of the class described the combination with the hollow knee of a headblock, of a center plate adapted to slide within the headblock, said plate being formed with a facially enlarged front portion having sets of guides cut therein, dogs adapted to slide within the guides, removable side plates retaining the dogs within the guides, means for retaining the center plate within the knee and means for operating the dogs backwardly and forwardly, as and for the 80 purpose specified. 85

20. 3. In a device of the class described the combination with the hollow knee of a headblock, of a center plate adapted to slide within the knee, the said center plate being formed with a facially enlarged front portion having on its sides, respectively, a series of similar guides, dogs adapted to slide within the guides, side plates retaining the dogs in position and held to the center plate by studs, a 95 vertical arm pivotally connected to each set of dogs, means for throwing the arms backwardly and forwardly, and means for retaining the center plate within the knee, as and for the purpose specified. 100

25. 4. In a device of the class described the combination with the hollow knee of a headblock, of a center plate formed with a facially enlarged front portion having on one side a series of similar transverse arcuate 110 guides, and on the other a similar set of guides with the arc reversed, sets of dogs adapted to slide within the arcuate guides, removable side plates retaining the dogs within the guides, a removable vertical arm connecting the individual dogs of the respective sets, adjustable means for retaining the center plate within the knee, and means controlled by a lever for throwing the arm forwardly and backwardly, as and for the 115 purpose specified. 120

30. 5. In a device of the class described the combination with the hollow knee of a headblock, of a center plate formed with a facially enlarged front portion having on one side a series of similar transverse arcuate guides and on the other a similar set of guides with the arc reversed, sets of dogs adapted to slide within the arcuate slots, removable side plates retaining the dogs within the guides, 125 130

said side plates being connected to the center plate by studs and retained in position by the inner side faces of the knee, vertical arms connecting the individual dogs of the respective sets, the said arms being retained in working position by the inner side faces of the hollow knee, screws adapted to hold the center plate within the knee and means controlled by a lever for throwing the vertical arms inwardly and outwardly, as and for the purpose specified.

6. In a device of the class described the combination with the hollow knee of a head-block, of a center plate formed with a facially enlarged front portion having on one side a series of similar transverse arcuate guides and on the other a similar set of guides with the arc reversed, sets of dogs adapted to slide within the arcuate guides, vertical arms connecting the individual dogs of the respective sets, a set of links pivotally connected to the vertical arms at their one end, and operating in slots formed in the facial enlargement of the center plate, a second set 25 of links pivotally supported on either side of the center plate and having one of their ends connected with the free end of the aforesaid links, and means for connecting and operating the latter links so that the vertical

arms with the dependent dogs are thrown 30 backwardly and forwardly, as and for the purpose specified.

7. In a device of the class described the combination with the hollow knee of a head-block, of a center plate formed with a facially enlarged front portion having on one side a series of similar transverse arcuate guides and on the other a similar set of guides with the arc reversed, sets of dogs adapted to slide within the arcuate guides, vertical arms 40 connecting the individual dogs of the respective sets, a set of links pivotally connected to the vertical arms at their one end, and operating in slots formed in the facial enlargement of the centre plate, sets of bell 45 cranks pivotally supported on either side of the center plate and having one of their arms, respectively, connected to the free end of the aforesaid links, a link joining the free ends of each set of bell cranks and links connecting 50 the latter links with the bifurcated end of a lever, as and for the purpose specified.

Signed at Winnipeg, in the Province of Manitoba, this 12th day of March 1907.

THOMAS MANLEY.
